(57) **CLAIM**

The ornamental design for a deck rail connector, as shown and described.

DESCRIPTION

FIG. 1 is an isometric view of the deck rail connector.

FIG. 2 is a front view of the deck rail connector.

FIG. 3 is a back view of the deck rail connector.

FIG. 4 is a side view of the deck rail connector.

FIG. 5 is the opposing side view of FIG. 4.

FIG. 6 is a top view of the deck rail connector; and,

FIG. 7 is a bottom view of the deck rail connector.

The broken lines in the drawings illustrate portions of the deck rail connector that form no part of the claimed design.
